UNITED STATES PATENT OFFICE.

ISIDOR KITSEE, OF PHILADELPHIA, PENNSYLVANIA.

TREATMENT OF COTTON-SEED.

No. 858,075.

Specification of Letters Patent.

Patented June 25, 1907.

Application filed May 26, 1905. Serial No. 262,435.

To all whom it may concern:

Be it known that I, ISIDOR KITSEE, of the city and county of Philadelphia, State of Pennsylvania, have invented certain new and useful Improvements in the Treatment of Cotton-Seed, (Case No. 258,) of which the following is a specification.

My invention relates to an improvement in the treatment of cotton seed.

As is well known, cotton-seed, now used principally for the production of the so-called "cotton-seed" oil, is subjected to one of the following processes for the purpose of extracting the oil. One process is to first destroy the short hairs or fuzz left on the hull of the seed after the ginning process and then to extract the oil through mechanical means. The second process is to first crush the seed to a fine powder and then through mechanical means sift the fuzz out of the crushed particles, whereby such fuzz may be used in the manufacture of articles, such as paper of a very low grade. Both processes have their disadvantages, and it is the aim of my invention to improve upon said processes and to produce a useful article out of the fuzz without necessitating the breaking up of the seed.

Persons versed in the art are aware that the pure cotton fiber is one of the best materials for the production of a soluble cellulose, either through a nitrating or through similar means.

In Letters Patent No. 789,977, and 35 789,978, granted to me May 16, 1905, I have described and claimed a method of making amorphous this fiber without removing it from the hull of the cotton seed.

According to the present invention a strong solution of chlorid of zinc is made and the fiber subjected to the action of this solution to simultaneously render the fiber soluble and dissolve it from the hull. In using the present method, however, I have found that the action is greatly facilitated when the temperature of this solution is raised.

To practice my invention, the following steps are preferably employed: First of all, the hull of the cotton seed is broken up and the kernel removed therefrom by any of the well known processes and appliances, and the hull with its covering of fuzz is then placed in a receptacle containing the chlorid of zinc in solution. As said above, I have found that the dissolving of the fiber in a zinc chlorid solution is greatly facilitated if

the temperature of the solution is raised, and I therefore preferably heat the solution during the time that the hull is contained therein. After a certain length of time, dependent on the strength and temperature of the solution, the fiber is entirely dissolved and the hull can then be removed from the solution by mechanical means, that is, by simply pouring the solution through a suitable netting or filter. I will state that at a low temperature about 24 to 36 hours are necessary for the dissolving process and at a raised temperature about 3 to 5 hours. If this process is carried on for a greater length of time than is necessary, part of the hull is also dissolved and the solution assumes a brownish color. Where such coloration is not objectionable, the dissolving process may be lengthened, as the resultant mass naturally gains in weight; but where the solution is desired to be clear, then the contents of the vessel should be subjected to inspection from time to time. The removed hull has a value as a fertilizing material, which greatly enhances the value of this process.

To enable persons to practice this my invention, even on a small scale, I illustrate in plan view the preferred apparatus for making soluble the adherent fiber on the seed, but it is obvious that other devices may be substituted therefor.

In the figure, 1 is a vessel containing the liquid 5.

2 is a vessel, the bottom of which is provided with the perforations 3. On this bottom are placed the broken-up hulls 4 to be treated.

6 is the flame or other source of heat.

It is obvious that the whole seed may be subjected to the action of the chlorid of zinc but I prefer that the kernels should first be removed.

Having now described my invention, what I claim as new and desire to secure by Letters Patent is:—

1. The method of treating cotton-seed which consists in first subjecting the seeds to a process whereby the hull is broken up, then to a process whereby the kernel is removed from said hull, then subjecting the broken-up hull with its adherent fiber to the action of a solution of chlorid of zinc for removing the fiber therefrom, and afterward removing said hull from said solution.

2. The method of treating cotton-seed which consists in first subjecting the seed to

a process whereby the hull is broken up, then to a process whereby the kernel is removed from said hull, then subjecting the broken-up hull with its adherent fiber to the action of a 5 solution of chlorid of zinc in the presence of high temperature for removing the fiber therefrom, and afterward removing said hull from said solution.

3. The method of treating cotton-seed 10 which consists in first subjecting the seed to a process whereby the hull is broken up, then to a process whereby the kernel is removed from said hull, then subjecting the broken-up hull with its adherent fiber to a chemical process 15 whereby the fiber is simultaneously made soluble and dissolved from the hull as an amorphous product.

4. In the method of treating cotton seed, the step of removing the adherent fiber there- 20 from, which consists in subjecting the hull with its adherent fiber to the action of a chemical agent capable of simultaneously rendering the fiber soluble and dissolving it from the hull.

25 5. In the method of treating cotton seed, the step of removing the adherent fiber there- from, which consists in subjecting the hull with its adherent fiber to the action of a chemical agent capable of simultaneously 30 rendering the fiber soluble and dissolving it from the hull, the temperature of the agent being raised during the period in which the hull is subjected to such action.

6. In the method of treating cotton seed, the step of removing the adherent fiber there- 35 from, which consists in subjecting the hull with its adherent fiber to the action of a solution of chlorid of zinc for simultaneously rendering the fiber soluble and dissolving it from the hull.

7. In the method of treating cotton seed, the step of removing the adherent fiber there- from, which consists in subjecting the hull with its adherent fiber to the action of a solution of chlorid of zinc for simultaneously 45 rendering the fiber soluble and dissolving it from the hull, the temperature of the chlorid of zinc being raised during the period in which the hull is subjected to such action.

8. The method of treating cotton seed, 50 which consists in first breaking up the hulls, then removing the kernels from the hulls, and then subjecting the broken-up hulls with the adhering fiber to the action of a solution of chlorid of zinc for simultaneously rendering the fiber soluble and dissolving it from the hull, and then removing the hulls from said solution.

In testimony whereof, I hereby sign my name in the presence of two subscribing wit- 60 nesses, this twenty-fifth day of May, A. D. 1905.

ISIDOR KITSEE.
